DESIGN FOR A GAME BOARD

Walter A. Merrill, Los Angeles, Calif.

Application September 24, 1935, Serial No. 58,685

Term of patent 3½ years

To all whom it may concern:

Be it known that I, Walter A. Merrill, a citizen of the United States, residing at Los Angeles, in the county of Los Angeles and State of California, have invented a new, original, and ornamental Design for a Game Board, of which the following is a specification, reference being had to the accompanying drawing, forming part thereof.

The figure is a plan view of a game board, showing my new design.

The said game board, while having a third dimension, is of no appreciable or material depth or thickness.

I claim:

The ornamental design for a game board, as shown and described.

WALTER A. MERRILL.
